FIG. 1 is a front view of a graphical user interface for a display screen or portion thereof showing a first embodiment of our new design; FIG. 2 is a front view of a graphical user interface for a display screen or portion thereof showing a second embodiment of our new design; and, FIG. 3 is a front view of a graphical user interface for a display screen or portion thereof showing a third embodiment of our new design.

The broken lines illustrating text, lines, numbers and images in the drawing show portions of the graphical user interface that form no part of the claimed design.
